UNITED STATES PATENT OFFICE

2,521,007

TUBE MAKING MACHINE

Ferdinand Heinmets, Allenwood, Pa.

Substituted for application Serial No. 392,240,
May 7, 1941. This application December 20,
1944, Serial No. 568,979

6 Claims. (Cl. 93—82)

1

My invention relates to tube making machines and has particular reference to machines for making continuous tubes from sheet material.

This is a substitute for my patent application, Serial No. 392,240, filed May 7, 1941 now abandoned.

My application has for its object to provide means to form a tube from a strip of sheet material by bending the strip around a mandrel and moving the thus-formed tube forward over the free end of the mandrel, the latter being supported at its rear end. For moving the tube I employ a plurality of clamps for the tube, the clamps being alternately reciprocated so that one clamp moves forward while the other clamps move rearward, the clamps being adapted to release the tube when they move rearward. A continuous movement is thus obtained for the tube.

In a modified embodiment of my invention I employ a plurality of rollers gradually bending the strip of sheet material around the mandrel.

My machine is especially suitable for making continuous tubes from such sheet material as paper, fiber, sheet metal, plastic material, etc.

I also provide means for sealing the edges of the tube together with the application of heat, using a thermoplastic cement, or any other suitable cementing means. For tubes made of thin sheet metal I provide means to form a locking means at the converging edges of the tube.

I also provide means for cutting off finished portions of the tube.

My invention is more fully described in the accompanying specification and drawings, in which:

Fig. 1 is a sectional elevational view of my machine;

Fig. 2 is a top plan view of the same;

Fig. 3 is a fractional sectional elevational view of a modified machine;

Fig. 4 is a similar view of another modification;

Fig. 5 is a similar view of still another modification;

Fig. 6 is a detail view of a clamp;

Fig. 7 is a similar view of a modified clamp;

Fig. 8 is a fractional view of a modified machine;

Fig. 9 is an end view of the same;

Fig. 10 is a fractional view of a machine employing rollers;

Fig. 11 is a sectional view taken on the line 11—11 of Fig. 10;

Fig. 12 is a sectional view taken on the line 12—12 of Fig. 10;

2

Fig. 13 is a sectional elevational view of a modified machine for making tubes from sheet metal;

Fig. 14 is a sectional view of a metal strip for use in the machine shown in Fig. 13;

Figs. 15, 16 and 17 are detail views showing successive stages in the formation of a lock seam;

Fig. 18 is a bottom view of the machine shown in Fig. 13;

Fig. 19 is a sectional view of a modified machine.

My tube making machine as shown in Figs. 1 and 2 consists of a base 1 supporting a bracket 2 on which is slidably mounted the rear end of a tubular mandrel 3. An additional support is provided by a guiding rod 4 attached to the mandrel and extending forward, being slidably supported in a bracket 5. The mandrel is used for forming a tube 6 from a strip 7 of a sheet material such as paper, fiber, plastic composition, metal, etc. The material is placed on the machine in a roll 8 supported on a shaft 9 in brackets 10.

The strip is delivered from the roll over a guiding roller 11 to gum applying rollers 12 and 13, the roller 13 being partly immersed in a tank 14 with a liquid glue 15 or other cementitious compound. The upper roller 12 presses the edge of the strip against the lower roller, thereby applying the composition to the edge of the strip. The strip is then passed over rollers 16, 17 and 18 through a drying chamber 19 where heat is provided by an electric heater 20 or other suitable heating device. A roller 21 is pressed against the roller 18 and is preferably positively driven by a suitable motor for moving the strips over the rollers. The strip is then passed through a former or forming die 22 consisting of a metal plate flat at the rear end where it is mounted on the raised outer ends of the upper portion of the bracket 2 under a clamping bar 23. The plate is gradually bent so as to converge around the mandrel 3 with sufficient clearance for the passage of the sheet material where it is formed into the tube 6. The former 22 is so shaped that the gummed edge of the material is placed over the other edge for cementing the edges together. The tube slides under a pressing block 24 which is pressed against the tube by a spring 25 whose tension is regulated by a screw 26. The block slides in an opening in a tubular member 27 supported on the bracket 5 mounted on the base 1 and supporting the front end of the former 22.

An electric heater 28 is provided in the tubular

member for heating the gum on the paper, the heater being preferably used when a thermoplastic glue is used for cementing the edges of the tube together. The tube is pulled through the former by a ring-shaped clamp consisting of two portions 30 and 31 pivotally supported on the rod 4 between its shoulders 32. The rod 4 is slidably supported on the bracket 5, the end of the rod 4 being secured to a bracket 51' extending from the mandrel 3. The lower ends of the clamp portions engage an eccentric cam 33 secured on a shaft 34 (Fig. 7).

The shaft is rotated by an electric motor 35 through gears 36, 37 so that twice during one revolution of the shaft, the clamp is tightened around the tube 6, clamping it against the front end of the mandrel 3. The shaft of the motor 35 extends through the bracket 2 and has a second pinion 38 driving a gear 39 on a shaft 40 journaled in brackets 2 and 41. The shaft 40 drives through bevel gears 42, 43 a vertical shaft 44 provided with a cam 45 engaging a pin 46 on the end of the mandrel 3. The gears are so proportioned that the mandrel 3 makes two complete oscillations during one revolution of the shaft 34, so that the tube 6 is clamped to the mandrel every time the latter is moved forward and released when the mandrel is moved back. The tube 6 is therefore moved forward step by step, remaining stationary when the mandrel is moved back.

In order to move the tube 6 continuously forward, additional clamps and mandrels are provided, a total of three sets of clamps and mandrels being shown by way of example in Figs. 1 and 2. The second set of clamps 47, 48 is pivoted on a rod 49 attached at the rear end to a lug 50 extending from a second mandrel 51 sliding inside the first mandrel 3. The latter has a slot 52 for the lug 50. A rod 53 extends from the second mandrel and has a pin 54 engaged by a cam 55 on a vertical shaft 56 rotated through gears 57, 58 by the shaft 40. The cam is so arranged that the second clamp, under action of an eccentric cam 59, engages the tube 6 for its forward movement at the end of the forward movement of the first clamp. The mandrel 51 has an enlarged end portion 60 of the same diameter as the first mandrel 3.

A third set of clamps 61, 62 engages an enlarged portion 63 on the end of a third mandrel 64 sliding inside the second mandrel and having an end portion 65 with a pin 66, engaged by a third cam 67 whose shaft 56' is rotated through gears 68, 69 by the shaft 40.

The mandrel 64 has a lug 70 passing through a slot 71 in the second mandrel and slot 52 in the first mandrel and connected with a rod 72 pivotally supporting the third set of clamps 61, 62 operated by an eccentric cam 73 on the shaft 34. The third set of clamps takes hold of the tube 6 for its forward movement at the end of the forward movement of the second clamp, the tube being therefore uninterruptedly moved forward. Springs 74, 75 may be provided to facilitate the return movement of the mandrels.

The tube may be delivered in a continuous length or it may be cut off in pieces of a desired length by a cutting off device shown in Figs. 1 and 2. The tube is cut by a disc knife 76 rotating on a block 77 sliding in a corresponding slot in a disc 78. The latter is mounted on a sleeve 79 rotating and sliding on a tube 80 supported on a bracket 81 extending from the base 1. The disc 78 is continuously rotated by a motor 75

82 through transmission gears 83, 84, 85, 86, a long pinion 87 and a ring gear 88 on the disc 78. The sleeve 79 has a flange 89 slidably engaged by a collar 90 which also engages a similar flange on a ring 90 sliding on the tube 80. The ring 90 has a rod 91 on which a clamp 92, 93 is supported. The clamp is pivoted on a shaft 93'. The lower ends of the clamp portions are engaged by an eccentric cam 95 on a shaft 95'. The cam is rotated by a gear 96 engaged by a long pinion 97 connected through a magnetic clutch 98 with the gear 84. The cam 95 is turned into an operative position when the clutch is energized, thereby clamping the tube 6 against a mandrel 99 slidably fitted on an extension 100 of the third mandrel 64. The mandrel 99 has a sharp edge 101 registering with the cutter 76. The mandrel 99, moving with the mandrel 64, moves also the knife 76 while the latter is rotated around the tube 6 by the motor 82.

The knife is pressed against the tube by a cable or chain 102 attached at one end to the block 77, the other end being attached to a collar 103 sliding on the sleeve 79. The collar is engaged by a hook 104 at the end of a rod 105 sliding in a bracket 106 extending from the bracket 81. A spring 107 keeps the rod under tension so that the collar 103 is pulled back when the knife is moved forward with the tube 6, the pull on the cable 102 causing the block 77 to move inward along the slot in the disc 78, pressing the knife against the tube until the latter is completely cut off.

A modified machine is shown in Fig. 3. It has a single stationary mandrel 108 and several sets of clamps 109, 110, 111 and 112, and 113 and 114 slidably pivoted on a shaft 115. The ends of the clamp members having tapering openings for tapering or conical ends 116 (Fig. 6) of rods 117, 118 and 119. The latter are alternately engaged by cranks 45, 55 and 67. The inner surfaces of the clamps are preferably provided with layers of rubber or other suitable frictional material in order effectively to engage the tube when the clamp jaws are moved together. The rods 117, 118 and 119 alternately move forward their clamps, forcing at the same time the tapering end portions between the clamp legs and thereby drawing the upper clamp ends together for clamping the tube. This form of the machine is especially suitable for making a tube of stiff cardboard or similar material which does not readily collapse under pressure of the clamps.

A variation of this machine is shown in Fig. 4 especially adapted for making tubes of thin paper or other soft material. The inner stationary mandrel 120 has an annular recess 121 for sliding collars 122. The latter are kept spaced apart by springs 123, 124, and 125, being positioned opposite corresponding clamps 109 and 110, 111 and 112, and 113 and 114. The clamps press the tube against their corresponding collars and pull the tube with the collars forward. Upon release of the clamps, the collars return to their original positions by the springs.

Another modification is shown in Fig. 5. The stationary inner mandrel 126 has slots 127 for pins 128, 129 and 130, connected to the collars 122. The pins are attached to the ends of rods 131, 132 and 133 operated by cams 45, 55 and 56 (not shown). The collars are thus positively moved together with the clamps 109-110, 111-112, 113-114.

Another modification is shown in Figs. 8 and 9 especially suitable for making heavy metal tubes.

The strip 134, which may be a relatively thick steel plate, heated if necessary, is rolled into a tube in a die block 135 having a tapering aperture 136 and continuously rotated by a gear 137 engaging gear teeth 138 on the periphery of the block. In order to prevent twisting of the strip 134, the mandrel 139 inside is also rotated as by a gear 140 engaging gear teeth 141 on the mandrel, the rotation being in direction opposite in the direction of rotation of the die block 135. The edges of the strip 134 may be beveled as shown in Fig. 9 and welded together by a block 134'.

Another modification is shown in Figs. 10, 11 and 12. The strip 134 is formed into a tube by a series of rollers 142, 143, 144 and 145. The rollers have progressively changing radius of curvature, angular rollers 146 being used for bending the edges of the strip around the mandrel 139'. The edges of the strip may be beveled as shown, so as to form a smooth joint which may be welded or soldered, or the edges may simply overlap each other, in which case the lower roller 145 may have a corresponding recess.

Still another modification is shown in Figs. 13 to 18 inclusive, specially adapted for making seamed tin tubes. The tubular mandrel 146 is reciprocated by an eccentric 45 together with a clamp 30, 31 operated by a rod 4. The mandrel is hollow, a stationary die block 147 being supported inside the mandrel on a rod 148 extending to the rear of the mandrel and supported on a suitable bracket (not shown). A strip of tin or other metal 149 is provided with a flange 150 at one edge (Fig. 14) and a double flange 151 at the other edge. The strip is fed through a former 22 in such a manner that the flange 150 enters the flange 151 as shown in Fig. 17. The thus-formed seam is drawn through a corresponding slot 152 (Fig. 18) in the block 147, the slot being so shaped as to bring the flanges together as shown in Fig. 15 and to bend them to one side as shown in Fig. 16. A slot 153 is provided in the former 22 for the block 147.

The seam may be formed on the outside as shown in Fig. 19, a die block 154 being placed outside the former for flanges 155 and 156 of the strip 149. This arrangement is especially suitable for metal tubes containing a paper or other insulating tube inside. The tube 149, as shown in Fig. 18, can be sprayed inside with a lacquer or other suitable protective substance, delivered through a stationary pipe 157 passing through a hole in the inner mandrel 148. The pipe 157 is closed at the end and provided with spraying apertures 158.

It will be understood that various features and principles of each of the embodiments of the invention above described or referred to may be utilized or substituted in the other embodiments.

While the invention has been described in detail with respect to certain particular preferred examples, it will be understood by those skilled in the art after understanding the invention, that various changes and further modifications may be made without departing from the spirit and scope of the invention, and it is intended therefore in the appended claims to cover all such changes and modifications.

What is claimed as new and desired to be secured by Letters Patent is:

1. A machine for making tubes comprising a base; a mandrel slidably supported at its rear end on the base; means to deliver a continuous strip of sheet material to the mandrel; means to form a tube around the mandrel of the sheet

material; means to reciprocate the mandrel, the mandrel being formed of a plurality of telescopic portions; a plurality of clamps encircling different portions of the tube on the different portions of the mandrel; means to successively reciprocate the mandrel portions and the clamps; means to cause the clamps to engage the tube during their forward movement and to disengage the tube when the mandrel portions and the clamps are moved rearward, thereby causing the tube to substantially continuously move forward on the mandrel.

2. A machine for making tubes comprising a base, a longitudinally extending mandrel supported above the base, means at one end of the mandrel to deliver a continuous strip of sheet material to the mandrel, means to form a tube of sheet material around the mandrel, collars slidably mounted on the mandrel and corresponding to the inner diameter of the tube and located within the formed portion of the tube, a plurality of clamp means, means to successively reciprocate the clamp means along the mandrel, means to successively operate the clamp means to engage the tube between the clamp means and the collars at one extreme of their reciprocating movement and to release the same at the opposite extreme thereby continuously moving the tube.

3. A machine as set forth in claim 2 wherein the collars slide along the mandrel on engagement of the tube between the clamp means and the collars and comprising in addition, means to restore the collars to their original position on release of the clamp means.

4. A machine for making tubes comprising a base; a mandrel supported on the base; means to deliver a continuous strip of a sheet material to the mandrel; means to bend the strip around the mandrel so as to join the edges of the strip, thereby forming a tube, the mandrel having an annular recess under the formed tube; a plurality of collars slidably supported on the recessed portion of the mandrel, the collars being of a substantially same diameter as the mandrel; springs on the recessed mandrel portion for keeping the collars in spaced relation to each other; annular clamps on the outside of the tube opposite the collars; and means to alternately reciprocate the clamps, the clamps being adapted to be tightened against the tube during forward movement, thereby clamping the tube against the corresponding collar, the clamps being released during rearward movement, the tube being thereby continuously moved forward.

5. A machine for making tubes comprising a base; a mandrel supported on the base; means to deliver a continuous strip of a sheet material to the mandrel; means to bend the strip around the mandrel so as to join the edges of the strip, thereby forming a tube, the mandrel being formed of several successive portions in axial alignment with each other, each portion being adapted to be reciprocated axially while the other portions remain stationary; means to alternately reciprocate the mandrel portions; annular clamps on the outside of the tube opposite the mandrel portions; means to reciprocate the clamps together with the corresponding mandrel portions; and means to render the clamps operative during forward movement and inoperative during rearward movement, thereby continuously moving the tube forward.

6. A machine for making tubes comprising a base; a mandrel supported on the base; means

to deliver a continuous strip of a sheet material to the mandrel; means to bend the strip around the mandrel so as to join the edges of the strip, thereby forming a tube, the mandrel being formed of several successive portions in axial alignment with each other, shanks extending from the mandrel portions to the rear; eccentrics 5 rotatively supported on the base at the rear of the mandrel operatively connected with the respective shanks; means to rotate the eccentrics, the eccentrics being arranged to alternately reciprocate the shanks; and means to clamp the tube to a forward moving mandrel portion, thereby continuously moving the tube forward.
